(57) **CLAIM**

The ornamental design for a liquid crystal display in viewfinder of a laser rangefinder, as shown and described.

DESCRIPTION

FIG. 1 is a front view of a liquid crystal display in viewfinder of a laser rangefinder;

FIG. 2 is an enlarged front view of a first image thereof; FIG. 3 is an enlarged front view of a second image thereof; FIG. 4 is an enlarged front view of a third image thereof; FIG. 5 is an enlarged front view of a fourth image thereof; FIG. 6 is an enlarged front view of a fifth image thereof; FIG. 7 is an enlarged front view of a sixth image thereof; and, FIG. 8 is an enlarged front view of a seventh image thereof showing all lighting states of the display.

The appearance of the liquid crystal display of the laser rangefinder transitions between the different lighting states shown in FIGS. 2-8. The process or period in which one image transitions to another forms no part of the claimed design.

The broken lines depict environmental subject matter only and form no part of the claimed design.
